Inventor:

Berthold A. Lange,

By Hugh N. Wagner,

Attorney.

UNITED STATES PATENT OFFICE.

BERTHOLD A. LANGE, OF ST. LOUIS, MISSOURI.

CRATE.

Application filed September 27, 1923. Serial No. 665,107.

To all whom it may concern:

Be it known that I, BERTHOLD A. LANGE, a citizen of the United States, residing at the city of St. Louis, in the State of Missouri, have invented certain new and useful Improvements in Crates, of which the following is a specification.

This invention relates to egg-crates or similar cellular packing structures, and pertains more particularly to a novel means for stiffening or bracing the individual layers or units thereof which are arranged in tiers and contain each a group of cells, whereby the walls of these units, which lack rigidity because of their extreme thinness and the flexible nature of the material of which they are fabricated, are reinforced against the tendency to lateral flexing, which shortens the transverse dimension of a row of cells, with the consequent compression and resulting breakage of the eggs or other fragile articles which may be contained in the pockets of the structure.

This invention contemplates the placing of a stiffening strip across a tier of cells at or near the middle thereof, so that its effectiveness will be more equally distributed toward either side along the length of the strip than if the strip were otherwise located on the structure. Otherwise stated, one of the objects of this invention is to place this stiffening strip at the point of maximum effectiveness, so that a minimum of material may be used therefor.

Another object is to provide two such stiffening strips, one for each row of intersecting partitions, so that lateral flexing of the partitions extending in each direction is minimized.

Another object is to allocate these two strips, one to the top of the tier, and the other to the bottom, so that the stiffening effect will be equalized between the top and the bottom.

A further object is to provide such stiffening means which shall be separate from the usual diaphragm or flat which is inserted between successive tiers or layers of cells.

Other objects and advantages will be apparent as the description proceeds.

In the accompanying drawings forming part of this specification, in which like numbers of reference denote like parts wherever they occur,

Figure 1 is a plan view of a single unit or

layer of cells embodying this invention; and

Figure 2 is a perspective view of a pair of superposed units or layers, separated by a diaphragm or flat, and to which this invention has been applied.

60

The crates 1 are preferably fabricated of strawboard and may be arranged in a plurality of as many tiers as desired or may be used singly, and consist of a series of strips or walls 2, intersecting another series 65 of strips 3, the same being preferably interlocked, which may be by any suitable means, such for instance as shown in the drawing, where slits 4 and 5 in the strips 2 and 3 face oppositely to each other and overlap the opposing strip. Notches 6 in the strip 2 and 3 receive the part of the opposing strip not cut away.

70

The usual flat or diaphragm 7 between tiers of crates provides a floor upon which 75 the eggs or other fragile articles in the pockets 8 can rest.

The strips 2 and 3 form partitions and side walls, and their ends terminate in projections 9. The lids or flats 7 project so as 80 to overlie the said projections 9 and thus to protect the same from being bent or broken. When they are bent or broken the breakage of eggs in the crate is increased.

To oppose lateral flexing or bending of 85 the walls 2 and 3, a perpendicular flange 10 and 11 are formed on the respective middle wall of each series of walls or strips 2 and 3, if there are an odd number of such walls in a series, and these flanges 10 and 11 may 90 project in either direction, as desired. If there are an even number of such walls in a series, or what amounts to the same thing, an odd number of rows of pockets 8, the flanges 10 and 11 are preferably located so 95 as to cover the middle row of pockets 8, being formed on either of the walls 2 and 3 adjacent the middle row of pockets 8.

The top edges 12 of the strips 3 lie everywhere in the same plane with the top edges 100 13 of the strips 2, except that in the middle row of pockets it is preferable that the top edges 12 lie slightly below the top edges 13, as shown at 14, so that the thickness of the flange 10 will fill the difference in height, 105 and the top 15 of the flange 10 is flush with the top edges 13. Similarly the bottom edges 16 of the strips 2 are raised or recessed at 17 to receive the flange 11 and allow the bottom side 18 of the same to lie in the same 110

plane with the bottom edges 16. This construction permits the diaphragm 7 to lie flat against the side of the crate 1.

The flanges 10 and 11 are formed integral with the respective strips from which they project, and thereby positively stiffen the said strips against lateral bending or flexing, and this rigidity is communicated from the flanged strip to its parallel fellows in the series through the intersecting walls of the other series. The location of the flanged strip in the middle results in less strain on those portions of the intersecting walls extending from either side of the middle than would occur if the entire strain were transmitted in one direction from one end of the crate to the other through all the rows of pockets, as is the case when the flange is at one end. Flanges 10 and 11, being arranged transversely with relation to one another, impart rigidity in the two directions in which it is needed. Furthermore, one flange being on the bottom and the other on the top, the strain is equally distributed between the lower and upper portions of the structure.

Having thus described this invention, I hereby reserve the benefit of all changes in form, arrangement, order, or use of parts, as it is evident that many minor changes may be made therein without departing from the spirit of this invention or the scope of the following claims.

I claim:

1. A crate comprising a series of parallel walls, a second series of parallel walls intersecting the first-mentioned series of walls, and means integral with one of the said walls nearest the middle of a series for bracing the said wall against lateral flexing, and a diaphragm for closing an open side of the crate.

2. A crate comprising a series of parallel walls, a second series of parallel walls intersecting the first-mentioned series of parallel walls, and separate means in each series and integral with one of the said walls near-

est the middle of its respective series for bracing the said walls against lateral flexing.

50

3. A crate comprising a series of parallel walls, a second series of parallel walls intersecting the first-mentioned series, and respective means in each series for bracing one of its walls nearest the middle thereof against lateral flexing, the said means being located one on each side respectively of the said crate.

55

4. A crate comprising a series of parallel walls, a second series of parallel walls intersecting the first-mentioned series of parallel walls, and respective means in each series and integral with one of the said walls nearest the middle of its respective series for bracing the said walls against lateral flexing, the said means being located respectively on opposite sides of the said crate.

60

5. A crate comprising a series of parallel walls, a second series of parallel walls intersecting the first-mentioned series, the respective wall of each series nearest the middle thereof having a perpendicular flange, the said flanges being located respectively on opposite sides of the said crate.

70

6. A crate comprising a series of parallel walls, a second series of parallel walls intersecting the first-mentioned series, the respective wall of each series nearest the middle thereof having a perpendicular flange integral therewith, the said flanges being located respectively on opposite sides of the said crate.

75

7. A crate comprising a series of parallel walls, a second series of parallel walls intersecting the first-mentioned series, a perpendicular flange on the nearest-to-the-middle-wall of a series, formed by bending a projection of the said wall over against a side of the crate, and recesses in the edges of the walls crossed by the said flange for receiving the same.

85

In testimony whereof I hereunto affix my signature.

BERTHOLD A. LANGE.
